By G. Jochum & Pitty

UNITED STATES PATENT OFFICE

JOHN L. NILSON AND JOHN F. PRINCE, OF CHICAGO, ILLINOIS

WINDSHIELD-CLEANER MOTOR

Application filed June 6, 1927. Serial No. 196,701.

Our invention relates to automatically operated, or power-driven cleaners, as distinguished from the hand operated devices. The objects of the present improvement are to provide an operating mechanism in small, compact and yet powerful form; one that will not obstruct a material portion of the field of vision or detract from the general appearance of a vehicle; a device that avoids the use of pistons and the like with their friction, leakages and packings, and one that is easily attached and removed. Another object is to provide a comparatively silently operating device, and a construction and arrangement of parts which cannot be disarranged from without, and which obviates lubrication.

With the above-named and other objects in view as will appear, our invention consists in the novel construction, combination and arrangement of parts hereinafter described in detail, illustrated in the accompanying drawing and more particularly pointed out in the appended claims.

In the drawing—

Figure 1 is a side view of a broken away portion of a wind shield and its frame with our improvement attached thereto.

Figure 2 is an enlarged section taken substantially on the line 2—2 of Figure 5.

Figure 3 is a top plan view of Figure 1.

Figure 4 is an enlarged section taken substantially on the line 4—4, of Figure 5.

Figure 5 is a section taken substantially on the line 5—5, of Figure 8.

Figure 6 is a section taken substantially on the line 6—6, of Figure 8.

Figure 7 is a side view of the spiral gear portion of the shaft broken away.

Figure 8 is a section taken substantially on the line 8—8 of Figure 5.

Figure 9 is a side view of one of the snap levers.

Figure 10 is a longitudinal section through the cylindrical valve member.

In the several views 2 represents the glass or transparent portion of a windshield, and 3 represents a usual U-shaped metal frame providing grooves for the transparent plate.

In any suitable place in the said frame 3 may conveniently be made a bore adapted to receive a squeegee or cleaner, driving shaft 4. The latter carries on its outer end (Figs. 1 and 2) an arm 5 on which is a bracket 6 to which is attached in any suitable manner a cleaner 8. The arm 5 is longitudinally adjustable to vary its reach. It is also laterally adjustable to adapt it to the varying thicknesses of windshields, by the provision of a suitable number of transverse bores 9, 10 and 11 in either one of which the arm is held against movement relative to the shaft 4 by means of a set screw 12 in a threaded bore 13 that intersects the bores 9, 10 and 11.

The shaft 4 is rotatably mounted in bearing bores 14 and 15, the former being through one side of the casing, which as a whole, is designated by the numeral 16. The said casing 16 is composed of two cup-shaped members 17 and 18 facing each other and provided, respectively, with flanges 19 and 20 by means of which the two sections of the casing are secured together, and between which is clamped a combination gasket and diaphragm 21.

The latter is moved or vibrated by air suctions introduced alternately within the casing chambers 24 and 25 on the respective opposite sides of the diaphragm. The movements of the latter are transformed by a helical screw connection 26 into an oscillating rotary movement in the squeegee-carrying shaft 4, the screw being engaged with threads 27 within a sleeve 28 that is longitudinally movable in a bore 29 that is concentric with the bore 15 and in the opposite side of the casing 16. On the inner end of the sleeve 28 are exterior threads 30 which pass through a corresponding bore in the diaphragm and are engaged on its opposite sides by threaded discs 31 and 32, which by being turned on

their threads toward each other clamp the diaphragm to the sleeve and cause the latter to move with said diaphragm and thereby turn the screw, or cam groove member 26.

5 The movement of the diaphragm also controls the movements of a single member valve 33 with a series of inlet and outlet ports therein and therethrough. Said valve 33 is preferably of cylindrical form and is snugly 10 fitted for a shuttle movement in a bore through a boss 34 on the inside of the cylindrical wall of the casing section 17, as shown in Figures 2, 4, 5 and 8. The connections between the diaphragm and the valve member 33 comprise a post 35 one end of which has threaded engagement at 36 with the discs 31 and 32 near their peripheries (Fig. 5), while the other end of said post (Figs. 5 and 8) has therein a slot 37 that is engaged by 15 an intermediate portion of an arch-shaped member 38 having two parallel runs 39 and 40 in the ends of which are notches 41 and 42 (Fig. 9) which engage an annular or circumferential slot 43 in each of a pair of brackets 20 44 and 45 arranged at opposite sides of the casing chamber. Each is provided with a 25 bent out lug portion forming a foot 46 which is secured by a screw 47, or otherwise to a boss 48 rising from the bottom of the member 30 16 of the casing.

Opposite the member 38 there is placed in co-operative relation a substantially similar member 49 and also provided with bearing notches such as 41 and 42 that are engaged 35 with the slots 43 in the brackets 44 and 45. The intermediate portion of the member 49 is engaged with a slot 50 (Figs. 5, 8 and 10) in the periphery of the valve cylinder 33. To the intermediate, opposing and parallel 40 runs of the members 38 and 49 are hooked the ends (Figs. 6 and 8) of coiled springs 51 and 52. These springs are tensioned to exert a stress on said parallel runs so that when the member 38 is moved through its diaphragm 45 connection past the line of dead center passing through the pivotal point 43 it will continue to swing, together with its companion member 49, under the spring tension and with a quick snap movement after the diaphragm 50 has reached the end of its movement, within the limitations of the width of an opening 33' made in the side of the boss or enlargement 34 for the reception of the valve engaging portion of the member 49. The movement 55 of the valve under its own spring power will, of course, be started by the diaphragm immediately before it has reached the extreme end of its own movement under suction power, sufficiently to bring the valve shifting or snap 60 over movement, past the above mentioned "dead center". If the opening of one valve and the simultaneous closing of the other valve were to take place under suction power under the brake of the squeegee and without 65 sufficiently violent or forcible momentum to

overcome said brake, a slow moving motor, as in windshield movement, would stop at the moment both ports were open and suction was divided equally between both sides of the diaphragm.

70 The shaft 4, carrying the helically grooved portion 26 has its inner bearing 15 in the bore of a nut 53 which is engaged with internal threads in a hollow boss 54 (Figures 5 and 8). The nut 53 has therein a slot 55 (Figure 8) 75 to be engaged by a screw driver. The valve 33, which is shown alone on an enlarged scale in Figure 10, is provided with two suction ports 56 and 57 that are in turn placed in communication with a conduit that includes 80 a casing outlet port at 58 through which suction is communicated from any suitable suction chamber, such as the inlet manifold of an explosion engine (not shown), by way of a flexible, or other tube or passage 59. The latter may be replaced by any other suitable 85 and less conspicuous channel such as, for instance, in whole or part, the channel space 60 indicated in Figure 3 between the edge of the glass and the bottom of the U-shaped frame 3, providing the glass of the windshield is so well packed in its frame as to 90 answer the purpose of a vacuum tube.

95 The port 58 enters the side of the casing as in Figures 1, 3, and 5, and communicates with a valve controlled lateral opening and valve seat 61 in the bottom of the bore in which the valve piston moves. Said port and valve seat 61 registers with the bore 62 that extends throughout the length of the valve 33, and it is always open to the ports 56 and 57 arranged at right angles to each other, as shown. Air is drawn from the chamber 24 by placing the port 56 in register with the port 64. Air is drawn from the other chamber 25 when its port 57 is, as in the several views, in register with a port 65 that leads to a port 66 at right angles thereto, and which port 66 passes through the dividing wall, or diaphragm, between the chambers 24 and 25 as shown in Figures 2 and 4. The foregoing refers to the suctions from the chambers. As suction is taking place in one of the chambers and the diaphragm moved thereinto a partial vacuum is created by the 110 enlargement or moving away from the opposite chamber. The latter is therefore opened to the outer air through suitable air inlet ports, as follows.

115 As, for instance, in Figure 5 the chamber 24 is shown open to the outer air, its condition at the end of the movement of the diaphragm to the left and commencement of suction in the chamber 25 to return said diaphragm to the right. The latter is therefore 120 open to the central suction bore 62, or to the air suction passages 66, 65, 57, 62, 61, 58 and 59. When the ports 56 and 64 are in register the chamber 25 is open to the outer air through an annular groove 67 on the pe- 125

riphery of the cylinder 33 being placed in register with the port 65 on one side of the cylinder and a bore 68 alined with it on the opposite side of the cylinder, the bore 68, as shown in Figures 2 and 4, leading to the outer air. On the other hand, when the ports 57 and 65 are in register 68 will be closed to 65 and a circumferential groove 69, similar to 67, will be alined, as plainly shown in Figure 5, with the port 64 and a port 68' similar to 68.

A space indicated 21' at the right hand end of the valve member 33, defines, like the space 33', the range of movement of the valve member. From the space 21' leads an opening 70 for a valve stem 71 having thereon a needle valve point 72 adapted to be seated at 61. The valve stem 71 is carried by a screw 73 having a knurled head 74 and threaded engagement with a bore 75 in the casing section 18, or its boss 34. By turning this screw the valve 72 may be opened or closed to start or stop the operation of the cleaner.

As shown in detail in Figure 7 the shaft 4 has shrunk thereon or otherwise secured thereto a collar 76 against which on the shaft are placed fiber washers 77 and 78, the former bearing against a ledge or shoulder 79 and the latter against the nut 53, so that when the latter is tightened against the parts 77 to 79 an air-tight joint will be made between the shaft and the chamber 24 and outer air.

Provision is made to filter the air entering the casing at 58, against dust and other foreign substances, which might clog up the air passages, the latter being rather fine or "needle passages". For this purpose a screen 80 is provided and the screen has a cover 80', both being shaped to form a chamber for cotton or other packing 81 and is secured by screws 82 over the ports 68 and 68' through which air is drawn from the outside. The cover 80' is provided with an opening 82' for the admission of air. 83 and 84 in Figure 1 indicate screws by means of which the casing section 17 is secured to the shield frame, but any other suitable fastening means may be employed.

The sleeve 28 is shown extending out of the casing section 18 through the opening 29 and on the extended portion is a knurled finger-grip part 84 by means of which the sleeve may be moved by hand to operate the cleaner manually, if desired, or made temporarily necessary, but for the purpose of the mechanical or suction operation the extension of the sleeve 28 and its bore 29 may be omitted and the length of the sleeve confined within the chambers 25 and 24.

60 What is claimed as new is:—

1. In a windshield cleaner operating mechanism, means for swinging the cleaner arm, said means embodying a casing, a screw shaft therein, a nut which co-operates with said shaft to rotate it, a valve, and a snap

over mechanism for operating the valve, said snap over mechanism being operatively connected with the said nut and valve.

2. A windshield cleaner operating mechanism embodying a cleaner arm movable parallel to the windshield surface, a shaft to which said arm is connected, said shaft having a screw thread portion, a nut engaging said screw thread portion, a valve, a snap over valve operating mechanism, and means embodying a diaphragm which is actuated by suction for actuating said valve mechanism.

3. A windshield cleaner operating mechanism embodying a diaphragm casing, a diaphragm dividing the interior of said casing into separate chambers, pneumatic actuating means for reciprocating said diaphragm, a valve, and a snap over valve actuating mechanism located in one of said chambers and connected with said diaphragm.

4. The combination with a pair of suction chambers, with a vibratory diaphragm, suction means for oscillating the latter, a shaft, telescoping threaded members which connect said diaphragm and shaft and convert the oscillatory movements of said diaphragm into rotary oscillating movements in said shaft, a valve mechanism, and a snap over movement for same connected with said diaphragm.

5. A windshield cleaner operating mechanism embodying a casing having a pair of suction chambers therein, a diaphragm between said chambers, suction means for moving said diaphragm to and fro, a valve mechanism for controlling the same, a rotary shaft alined with the path of movement of said diaphragm, and a snap over movement included in said valve mechanism and housed within one of said chambers.

6. A windshield cleaner operating mechanism embodying a casing, an actuator member movable therein, a valve chamber, ports leading from the valve chamber to opposite sides of the actuated member, a suction port leading from said valve chamber, a tubular valve for connecting either of the first recited ports with said suction port, said valve being responsive in its operation to the actuation of said actuator member, and a needle valve accessible from the outside of the said casing, and extending through said valve for controlling the said suction port.

7. A windshield cleaner operating mechanism embodying a casing, an actuator member movable therein, a valve chamber, ports leading from the valve chamber to opposite sides of the actuated member, a suction port leading from said valve chamber, a tubular valve for connecting either of the first recited ports with said suction port, said valve being responsive in its operation to the actuation of said actuator member, and a needle valve accessible from the outside of the said

casing, and extending through said valve for controlling the said suction port, both of said valves being operable independently with respect to each other.

5 In testimony whereof I, JOHN F. PRINCE, have signed my name to this specification, on this 6th day of May, A. D. 1927.

JOHN F. PRINCE.

10 In testimony whereof I, JOHN L. NILSON, have signed my name to this specification, on this 6th day of May, A. D. 1927.

JOHN L. NILSON.
